METHOD OF STABILIZING SLIDE AREAS

Ray R. O'Neal, San Francisco, Calif.

Application August 7, 1948, Serial No. 43,080

4 Claims. (Cl. 61—36)

1

This invention relates to an improved method of draining excess water from slide areas.

The present invention is primarily a system which embodies the drilling of a plurality of laterally inclined holes into the slide body or slide area and the firing of the walls of the holes to solidify and make them porous.

This invention is particularly well suited for use in the drainage of slide areas which are composed of clay or clay-like substances. This type of material when present in certain deposits brings about undesirable earth displacements which are difficult to control and which are responsible for a great many destructive slides.

Speaking in geological terms, clay is a hydrous aluminum silicate generally mixed with powdered feldspar, quartz, sand, iron oxides, and certain other minerals. Wet clay in its natural form is plastic and tenacious, but when heated sufficiently, it becomes porous, hard and brittle.

The firing or burning process in connection with clay is called metasomatism. Thus, when wet clay is heated, the first effect is to decrease its moisture content. The clay then becomes dry, but is not chemically altered; it does not cease to be plastic when cooled and moistened again. If the temperature continues to be raised, however, the chemically combined water is separated and the clay undergoes a molecular change, which change prevents the clay from taking up water again, except mechanically. Thus, suitably fired clay will retain its porosity but ordinarily will not be restored to a plastic state when in contact with water. It might also be noted here that on further heating the clay tends to undergo partial fusion, which result is not desired here.

The primary object of this invention is to provide an improved drainage method for slide areas which will afford means for intercepting seepage or other water contained in the slide area and which will conduct it to a free outlet, thereby checking the displacement of the slide body.

Another object of this invention is to provide a drainage system that will be of considerable less cost to install and maintain than other slide preventative structures now commonly used, and one which is highly efficient in its operation.

A further object of this invention is to stabilize a slide body and check its downward movement by means of a series of rigid tubular reinforcing members spaced throughout the slide body.

These objects and advantages will be best understood by reference to the detailed description below, together with the accompanying drawing in which:

2

Fig. 1 is a cross-section of a typical slide area which has been treated in accordance with my invention;

Fig. 2 is an enlarged sectional view of one of the tubular drainage members located in the slide area; and

Fig. 3 is a similar view showing a portion of the firing apparatus operatively mounted therein.

10 The underlying theory of this invention is based upon the fact that slide areas are mostly composed of clay and clay-like materials, which areas after the introduction of excess water from rainfall, nearby springs or other underground water sources, often become moving bodies.

The density and nature of clay and clay-like materials is such that water seeping into them does not drain off rapidly. The clay material then becomes plastic or semi-fluid with water 20 acting as a lubricating agent often setting the whole slide mass into motion.

However, by drilling a plurality of laterally inclined holes into or substantially through the slide body or area and then baking or firing the 25 walls of the holes, a most effective system for draining off excess water is provided. This firing process will form a porous, pottery-like casting similar to drainage tile around each hole. However, it must be noted here that the clay 30 material fired in accordance with this method should not be fused and thereby have the density of soilpipe, but should be highly porous.

Referring to the drawing, the numeral 1 indicates a typical slide area comprising a body of 35 wet clay-like or other similar material which by reason of its moisture content or its peculiar drainage pattern has become or is apt to become subject to sliding.

In carrying out this invention, a plurality of 40 laterally inclined holes 2 are first drilled with suitable drilling equipment such as an auger from the exposed lateral face of the slide body to points near or at the latter's opposite unexposed side.

45 A suitable pattern which may be used in this method is the drilling of the lateral holes with an approximate 3 per cent rise from their discharge ends to their opposite ends for water drainage from the slide area 1. These holes 50 should extend from the exposed face of the slide area 1 preferably to the inner unexposed side of same area 1 and should be staggered and distributed in such a way as to afford good coverage of the slide area 1.

55 The next step in carrying out this invention is the firing of the walls or sides of the drain holes. The firing operation is carried out by

means of suitable heating equipment which bakes the walls of the holes 2 to the desired temperature depending upon the properties of the clay as revealed by a soil analysis of the slide area.

It is to be understood that any suitable type of firing apparatus may be used in applying heat to the walls of the holes 2, such as an outer pipe 3 having a tubular conduit 4 extending therethrough and spaced from latter's walls. The flame, supplied by the gaseous fuel passing through the conduit 4 is supported by suitable air passing through the interior of the pipe 3. Electrical or other suitable heating equipment may also be used.

The object of the firing in this process is to provide a highly porous, durable casing 5 around each drainage hole 2 through which the water from the wet slide area 1 may drain. It is to be noted that the burning or firing of the clay-like material at the sides of the holes is an important step in this process, for the action of the heat brings about certain chemical decompositions and recombinations which alter the physical character of the material and thereby makes it porous.

The temperature for firing the drain holes 2 will vary according to the type of clay found in the slide area. By variation in composition, clays are divided into three broad classifications, black, plastic, and sandy, and the temperature required for driving off the water in chemical combination in each clay type will be determined by the composition of the particular clay type. However, for all practical purposes, a temperature ranging from 1000 degrees F. to 1400 degrees F. is sufficient to drive off the water in chemical combination in all common clays and to bake them suitably.

Care must be taken when firing these drain holes 2, for too excessive a temperature, say 1800 degrees F. or 2000 degrees F. or more, will cause the iron oxides of the clay to fuse to form a glassy, non-porous substance called "fusible glass." This process is called "vitrification" and if employed here would defeat every purpose of the invention, for instead of producing a porous casing 5 through which the excess water of the slide area 1 could drain, the firing under these circumstances would produce a non-porous, glassy, impervious casing which would be incapable of absorbing water.

Water seeping through the porous walls 5 of each casing flows downwardly therethrough and is drained from the slide area. In ordinary practice a roadside drain ditch is provided at the base of the slide area to convey the drained water away.

By means of the drainage system comprising

this invention, the excess water is continuously drained from the slide body, thereby removing what is commonly recognized as the cause for most slides.

5 The distribution of the rigid tubular casings throughout the slide body in accordance with the present invention provides a reenforcing structure which holds the slide body in place.

It is to be understood that this invention may be employed to stabilize fills as well as slide areas. The term "fills" is used here to refer to any artificial or man-made bodies of clay or clay-like material which contain excess water and are subject to displacement.

15 What I claim is:

1. A method of stabilizing clay or clay-like slide bodies having a substantial moisture content which comprises forming a plurality of laterally inclined holes in such a slide body, 20 and firing the sides of the holes to solidify and make porous the said sides of the holes.

2. A method of stabilizing clay or clay-like slide bodies having a substantial moisture content which consists in drilling a plurality of 25 laterally inclined holes through the slide body, and firing the sides of the said holes to solidify and make porous the material immediately surrounding the holes.

3. A method of stabilizing clay or clay-like slide bodies having a substantial moisture content which comprises drilling a plurality of laterally inclined and spaced holes substantially through such a slide body, the said holes having their discharge ends at the exposed lateral face 35 of the slide body and the said holes being disposed with their discharge ends at lower levels than their opposite ends, and firing the sides of the holes until porous, rigid casings are formed around the holes.

40 4. A method of stabilizing clay or clay-like slide bodies having a substantial moisture content which comprises forming an elongated inclined hole in such a slide body, the said elongated hole being arranged to convey liquid collecting therein to a point at an edge of the said slide body, and firing the sides of the said hole to solidify and make porous the said sides of the hole.
